United States Patent Office

Des. 213,531
Patented Mar. 11, 1969

213,531

PEN

Noboru Wakai, Tokyo, Japan, assignor to Dai Nihon Bungu Kabushiki Kaisha (also trading as The Japan Stationery Co., Ltd.), Tokyo, Japan, a corporate body of Japan

Filed Dec. 27, 1967, Ser. No. 9,945

Term of patent 3½ years

U.S. Cl. D74—17
Int. Cl. D19—06

FIG. 1

FIG. 2

FIG. 3

FIG. 4

FIG. 5

FIG. 1 is a side perspective view of a pen showing my new design;

FIG. 2 is a side elevational view thereof as it appears without the cap;

FIG. 3 is a top plan view of FIG. 1 rotated 90 degrees to the right;

FIG. 4 is a top plan view of FIG. 2; and

FIG. 5 is a bottom plan view thereof.

I claim:

The ornamental design for a pen, as shown.
